DISPENSING PACKAGE

Ralph C. Russell, Arden, Del., assignor to E. I.
du Pont de Nemours & Company, Wilmington,
Del., a corporation of Delaware

Application January 2, 1940, Serial No. 312,107

1 Claim. (Cl. 229—51)

This invention relates to a package comprising a plurality of layers of limp material having a tough, flexible covering, especially a stack of pliant or lithe paper sheets wrapped in a non-fibrous cellulosic sheet. More particularly it appertains to a displaying and dispensing package comprising folded tissue paper units, a regenerated cellulose sheet wrapper and an opening device.

The invention had for an object the production of a package comprising a transparent wrapper and folded tissues which could be easily opened. Another object was to design such a package which could be used to dispense the folded tissues, a tissue at a time. Still another object was to provide regenerated cellulose sheet wrapped stacks of tissue-like material with a readily available opening device. A general advance in the art, and other objects which will appear hereinafter, are also contemplated.

A preferred embodiment of the invention is illustrated in the accompanying drawing, in which:

Figure 1 is a perspective view of the package;

Figures 2, 3 and 4 are partial perspective views illustrating stages in the opening of the package;

Figure 5 is a view of the wrapper, with its adhered opening strip, before it is applied to the stack of tissues; and

Figure 6 is an exaggerated isometric sectional view of the wrapper and a tray for the stack of tissues.

Figure 7 is a partial perspective view similar to Figures 2, 3 and 4, showing the opened dispensing package and a tissue sheet partially removed.

For convenience of illustration and explanation, a package of tissue handkerchiefs of conventional size will be described. These tissues are about $8\frac{1}{2} \times 9\frac{1}{2}$ inches, and, to facilitate dispensing from the original package, are folded over from opposite edges $1\frac{1}{8}$ and $1\frac{1}{4}$ inches, respectively, on lines parallel to the long dimension. The resulting unit is $4\frac{1}{2} \times 9\frac{1}{2}$ inches. In the illustrated package 100 of these tissue paper sheets are stacked in a partial tray and wrapped. The resulting package is about $2\frac{1}{4} \times 4\frac{1}{2} \times 10$ inches. A tearing strip approximately $\frac{3}{4}$ inch wide and extending lengthwise of the package and wrapper, is provided. Obviously the invention is not limited to this, particular package.

Similar characters refer to similar parts

throughout the drawing, in Figure 1 of which a package comprising a stack of tissue sheets 12, disposed in a cardboard tray 13, are covered with a transparent sheet of regenerated cellulose 11.

5 The cellulosic sheet, before being wrapped about the partial tray and its contents, is shown in Figure 5. It is wrapped in such a way that an overlapping seam is formed on the bottom of the tray. The overlapping edges are shown at 16 and 17 in Figures 5 and 6. The edges of the wrapper at the end of the tray are tucked and folded in a conventional manner, as shown in Figures 1, 2, 3 and 4.

The tray 13 has ends, as shown very clearly in Figure 6. In the preferred embodiment most of the sides of the tray are cut away, as shown in Figure 1. Part of the bottom of the tray may be cut away, if desired.

20 The opening means comprises a strip of regenerated cellulose 14, adhesively secured to the inside of the wrapper, and, generally, notches or slits 15 approximately $\frac{1}{4}$ inch long in the wrapper on each side of the ends of the strip. The notches enable the ends of the strip and attached part of the wrapper to be lifted sufficiently to permit grasping by the fingers.

25 To open the package it is only necessary to grasp the end of the strip or tape and pull it back over the package. The progressive action in opening is shown in Figures 2, 3 and 4. Since the tearing tape is adhesively secured to the wrapper, a strip of the wrapper of approximately the same size as the tape is torn away in the opening operation. The tear progresses smoothly, leaving clean edges for the resulting open slit in the top of the package wrapper. This opening enables the tissues to be dispensed without destroying the general shape and character of the package.

30 40 45 Transparent regenerated cellulose sheet is the preferred wrapping material, but other similar non-fibrous sheet material, such as lowly etherified cellulose (for example, low substituted methyl cellulose and low substituted ethyl cellulose), and lowly esterified cellulose may be satisfactorily employed. The organic solvent soluble type cellulose substitution derivatives, such as cellulose ethers and esters (for example, cellulose acetate and ethyl cellulose) are also suitable. Translucent products may be used in some instances.

40 45 Although somewhat less desirable, fibrous sheet such as paper, glassine paper, etc., suitably impregnated or otherwise treated to provide translucency, may also be utilized for the wrapping.

If desired, the sheet wrapping material may be coated or otherwise treated to render it water resistant, moistureproof, heat-sealable, etc. It may be colored as by dyeing or pigmentation, and may carry printing.

Generally the tearing strip is secured to the wrapper on the surface which becomes the inner surface of the wrapper when the package is formed. A tearing strip on the outside is practical, but not so desirable. Preferably the tearing strip runs parallel to the grain of tearing (i. e., the longitudinal direction of manufacture). As will be apparent from the drawing, the folded over end portion bearing the tearing strip is on the outside.

The packaged material may be any limp sheet-like material. Inexpensive paper products such as napkins, handkerchiefs, and the like, are products with which the greatest advantages are obtained. Preferably the units are stacked in a tray-like receptacle before wrapping, and they may be interleaved to facilitate dispensing. The manner of folding and location of the fold lines may vary, including in addition to the center folding illustrated in Figure 7, for example, the well known edge folding.

Preferably the supporting tray is of light cardboard or like stiff material. Cut-out portions for utilitarian or esthetic purposes, for example, to facilitate viewing and to enhance appearance, may be located in the sides, bottom, etc., so long as the rigidity of the package is not below that necessary to enable wrapping.

It is not necessary that the tray be cut in the design shown in the drawing. One or both side edges may be cut out in artistic or advertising designs, and may bear attractive printing matter. Generally a portion of the side is removed because this permits a better display or exposure of the contents than would be possible with a high-sided, high-ended tray coextensive with five sides of the package.

The manner of sealing the package is relatively unimportant. Adhesives, particularly the heat-sealable type, are satisfactory. Adhesive tape is also suitable. Ordinarily the tray of tissues is completely enclosed and the overlapping portions of the wrapper sealed together.

The opening tape may conveniently be a regenerated cellulose ribbon of the type disclosed in U. S. A. Patent No. 1,406,148 (Brandenberger), but other tearing strips, for example, laminated cellulosic ribbons, fibrous or woven materials such as paper strips, fabric ribbons and the like, may be satisfactorily employed. Like the wrapper, the tape may be of various non-fibrous materials,

and may be colored. It may be located at one edge or centrally (as shown in the drawing) of the package, or may occupy a position intermediate these places.

5 The present invention provides for the full, clear and attractive display and exposure of an article of commerce which depends upon attractive exposition of its color and tints, freshness of condition, etc., for its salability. The present package has the advantages both of displaying the product and of providing a convenient receptacle (and method) of dispensing the packaged product a layer at a time until exhausted.

10 The package is very inexpensive to produce, and serves admirably for the display of the contents. It provides an extremely simple, effective and satisfactory method of opening the wrapper and dispensing the contents without disrupting the package as a whole. All portions of the wrapper other than the narrow dispensing opening remain 15 intact and in place, protecting the contents until exhausted. It eliminates cardboard dispensing opening reinforcements in packages of this type.

15 As many apparently widely different embodiments of this invention may be made without departing from the spirit and scope thereof, it is to be understood that this invention is not limited to the specific embodiments thereof except as defined in the appended claim.

I claim:

20 A dispensing package comprising a stack of interfolded limp tissue paper sheets in an elongated rectangular open-topped integral cardboard tray whose corners delineate the corners of the package, the ends of said tray being full and the sides being partly cut away to expose the folded sheets to view, a rectangular transparent regenerated cellulose sheet wrapper therefor having a regenerated cellulosic tearing tape extending medially thereacross, the said wrapper being 25 folded about the tray with its overlapping edges forming a seam across the bottom and the tear strip extending longitudinally across the top of the tray, the wrapper having folded, tucked and sealed ends at the respective ends of the tray including down-turned exposed tabs extending partway down the ends of the tray and exposing the ends of the tape, said tape being on the inside 30 of the said wrapper and having an end accessible to permit grasping with the fingers, said tape also being secured to the wrapper with sufficient tenacity to cause shearing out of a conterminous section of the wrapper to provide dispensing aperture across the top of the package when the tape is pulled away from the package.

RALPH C. RUSSELL.
